UNITED STATES PATENT OFFICE.

JOHN ORISON VAN CLEAVE, OF SIDNEY, COLORADO.

HAY-STACKER.

1,038,992.

Specification of Letters Patent. Patented Sept. 17, 1912.

Application filed September 9, 1910, Serial No. 581,212. Renewed February 21, 1912. Serial No. 679,187.

To all whom it may concern:

Be it known that I, JOHN ORISON VAN CLEAVE, a citizen of the United States, residing at Sidney, in the county of Routt, 5 State of Colorado, have invented certain new and useful Improvements in Hay-Stackers; and I do hereby declare the following to be a full, clear, and exact description of the invention, such as will enable 10 others skilled in the art to which it appertains to make and use the same.

This invention relates to hay loaders.

The principal object of the invention is to improve and simplify the general construction of devices of this character.

A second object of the invention is to so arrange the hoisting means in a hay loader provided with a pitching fork that the movement of this fork will closely resemble the 20 movement of an ordinary hay fork when manipulated by hand so that the initial raising of the hay is accomplished at a relatively slow speed while the final or discharge movement of the fork is at a relatively high speed.

A third object of the invention is to provide a novel arrangement of hoisting means for such a fork wherein a greater power will be exerted during the initial movement 30 of the fork than at the end of the movement of said fork.

With the above and other objects in view the invention consists in general of certain novel details of construction and 35 combinations of parts hereinafter fully described, illustrated in the accompanying drawings, and specifically set forth in the claims.

In the accompanying drawings, like 40 characters of reference indicate like parts in the several views, and Figure 1 is a side elevation of a hay loader constructed in accordance with this invention with the fork shown in its lowered position. Fig. 2 is a similar view showing the fork in its raised 45 position. Fig. 3 is a vertical longitudinal section through the hay loader. Fig. 4 is a plan view of the loader. Fig. 5 is a detail perspective view of one of the pivots of 50 the secondary frame forming a part of this invention.

The loader comprises a main frame which includes a pair of longitudinal skids 10 by 55 which the loader is supported on the ground so that it may be transported from one place to another. At the rear end of these skids

are uprights 11 which are connected at their upper ends by a cross beam 12 and the skids are held apart at their lower ends by a cross beam 13. Furthermore the parts are 60 braced by the usual diagonal brace 14. Extending from the upper end of each of the members 11 downwardly and forwardly are frame members 15 which have their lower extremities connected with the forward ends 65 of the skids 10. Uprights 16 are fixed to the skids and serve to brace the members 15 at points just below journal bearings 17 for the pivots of the secondary frame herein-after referred to. Between the skids 10 at 70 the forward ends are diagonal members 18. There is also employed a secondary frame 75 which consists of a pair of spaced triangular frames each of which has a base member 19 and diagonal members 20, the latter having their apical extremities connected to a perpendicular member 21. The members 19 are connected by a bar 22 whereon are fixed plates 23 carrying pintles 24 which engage in the journal bearings 17. This 80 member is arranged in the angle between the members 21 and 19. This triangular frame has its base vertical when the fork is lowered and in referring to the different parts of said frame herein-after it will be 85 assumed that this is the position of the frame normally. The upper ends of the base members 19 are connected by a cross bar 25 while the lower ends are connected by a cross bar 26. The verticals 21 extend 90 beyond the apex of the respective triangle and are connected by a cross bar 27. The extremities of these perpendiculars are furthermore connected by a rod 28.

The fork proper comprises transverse 95 members 29 having fork teeth 30 secured thereto and extending forwardly therefrom. These members 29 also support a back rack 31. Attached to the fork are spaced arms 32 which are pivoted upon the rod and these 100 arms are braced to the rack 31 by braces 33.

Extending upward from the members 15 are uprights 34 and diagonal bracing 35 extends horizontally between said uprights and the members 15. Connecting the upper 105 end of said uprights 34 is a bar 36 which is provided with suitable journals so that the bar is pivoted to rotate between said uprights. Extending rearwardly from the bar 36 is a series of fingers 37 forming a discharging platform and these fingers are connected intermediate their ends by a mem-

ber 38. Hinged to the extremities of the member 38 are supports 39 which pass through guides 40 fixed to the members 11 and said supports 39 are secured in adjusted relation in these guides by bolts 41. By this means the rear end of the platform may be raised or lowered as desired. Secured to the member 25 intermediate its ends is a pulley 42 and a second pulley 43 is secured intermediate the ends of the member 27. Secured centrally of the cross bars 18 is a third pulley 44 and mounted on the rod 28 and centrally thereof is a fourth pulley 45. Secured intermediate the ends 15 of the member 13 is a guide pulley 46. A cable 47 has one end secured to the fork frame 29 and is led over the pulley 42 and pulley 43 around the pulley 44, over the pulley 45, and around the pulley 46 out of 20 the side of the device so that a draft animal may be attached to travel laterally of the loader.

In the operation of the device the hay gathered on the fork 30 is lifted by stress 25 upon the cable 47. At first the action is to rotate the triangular secondary frame about its pivots until the pulleys 44, 45 and 46 are brought into such alinement that the cable lies straight between the pulleys 44 and 46. 30 Then the triangular frame ceases to rotate. During this part of the operation the frame has been lifted by the cross bar 26 which constitutes a stop member to limit the movement of the arms 32 relative to the frame in one direction. After this initial movement 35 has been accomplished further stress upon the cable 47 will rotate the arms 32 about their pivots until the fork braces 33 engage the member 36 which thus acts as a stop member to limit the movement of the arms 40 rearwardly. By reason of the peculiar arrangement of the cable the initial movement is relatively slow while the final movement is very rapid so that the hay is thrown 45 violently over the delivery platform toward the rear of the machine. Furthermore the initial movement is accomplished with ease on account of the arrangement of the pulleys affording the same effect as that of a tackle having a single block at each end while a final movement which requires less power, is simply that of a single block and thus does not afford any increase of power. 50 In the returning of the device upon slackening the cable the triangular frame first rotates until the lower ends of the arms 15 are brought to the rear of the center of gravity. The upper ends of these arms then move out and strike the stop member 26 and the triangular frame and fork revolve together 55 to the initial position.

There has thus been provided a simple and efficient device of the kind described and for the purpose specified.

60 65 It is obvious that many minor changes

may be made in the form and construction of this invention without departing from the material principles thereof. It is therefore desired to confine the invention to the exact form herein shown and described but it is wished to include all such as come within the scope of the appended claims.

Having thus described the invention what is claimed as new, is:—

1. In a hay loader, a main frame, a secondary frame pivoted to the main frame, a loading fork provided with arms pivoted to the secondary frame, and hoisting means arranged to first rotate the secondary frame on its pivots and then rotate the fork on its 75 pivots.

2. In a hay loader, a main frame, a secondary frame pivoted to the main frame, a loading fork provided with arms pivoted to the secondary frame at points remote 80 from the pivots connecting the main and secondary frames, a stop member on the secondary frame to limit the movement of the fork arms in one direction relative to said frame, and hoisting means arranged to first rotate 85 the secondary frame on its pivots and thereby raise the fork and then rotate the fork on its pivots to complete the movement of said fork.

3. In a hay loader, a main frame, a secondary frame of substantially triangular form, pivots connecting said main frame with the base of said triangular frame, the connection of said pivots with the triangular frame being intermediate the extremities of the base, a loading fork, arms fixed to the loading fork and having their free extremities pivoted to the apex of the triangular frame, a stop member forming part 100 of said triangular frame and against which said arms engage to limit the movement of the arms in one direction relative to said frame, the base of said triangular frame being vertical when the fork is lowered, a pulley fixed to the triangular frame adjacent its 105 upper angle, a second pulley attached to the triangular frame adjacent its apex, a third pulley attached to the main frame forward of and below the triangular frame, a fourth pulley fixed to the triangular frame adjacent its 110 apex, and a cable having one end attached to the fork and led around the pulleys in the order named.

4. In a hay loader, a main frame, a secondary frame pivoted to the main frame, a 115 loading fork provided with arms pivoted to the secondary frame, and hoisting means arranged to first rotate the secondary frame on its pivots and then rotate the fork on its pivots; in combination with a discharging platform carried by said main frame and having its forward portion arranged to be engaged by said fork when the latter is raised.

5. In a hay loader, a main frame, a sec- 130

ondary frame pivoted to the main frame, a loading fork provided with arms pivoted to the secondary frame at points remote from the pivots connecting the main and secondary frame, a stop member on the secondary frame to limit the movement of the fork arms in one direction relative to said frame, and hoisting means arranged to first rotate the secondary frame on its pivots and there-
5 by raise the fork and then rotate the fork on its pivots to complete the movement of said fork; in combination with a discharging platform carried by said main frame and having its forward portion arranged to be engaged by said fork when the latter is raised.
10 6. In a hay loader, a main frame, a secondary frame of substantially triangular form, pivots connecting said main frame with the base of said triangular frame, the connection of said pivots with the triangular frame being intermediate the extremities of the base, a loading fork, arms fixed to the loading fork and having their free extremities pivoted to the apex of the triangular
15 20 25

frame, a stop member forming part of said triangular frame and against which said arms engage to limit the movement of the arms in one direction relative to said frame, the base of said triangular frame being perpendicular when the fork is lowered, a pulley fixed to the triangular frame adjacent its upper angle, a second pulley attached to the triangular frame adjacent its apex, a third pulley attached to the main frame forward of and below the triangular frame, a fourth pulley fixed to the triangular frame adjacent its apex, and a cable having one end attached to the fork and led around the pulleys in the order named; in combination with a discharging platform carried by said main frame and having its forward portion arranged to be engaged by said fork when the latter is raised.

In testimony whereof, I affix my signature, in presence of two witnesses.

JOHN ORISON VAN CLEAVE.
